UNITED STATES PATENT OFFICE

2,023,435

REFRIGERATION

Frank Desnoyers Peltier and Clyde Edward Ploeger, Evansville, Ind., assignors to Servel Inc., New York, N. Y., a corporation of Delaware

Original application July 6, 1928, Serial No. 290,871. Divided and this application October 31, 1930, Serial No. 492,382

2 Claims. (Cl. 62—95)

This application is a division of our co-pending application Serial No. 290,871, filed July 6th, 1928, and is to be considered as relating back to applications Serial Nos. 152,339 and 152,902, for common subject matter and to the rights incident thereto.

Our invention relates to refrigerating apparatus and more particularly to the type of apparatus embodying a closed cycle including compressor, condenser and evaporator. Still more particularly our invention relates to the evaporator of such a system.

Amongst various objects of our invention are: To produce a novel cycle of flow for refrigerant fluid; to provide a novel method and apparatus for lubricating a refrigeration system and for conducting lubricant within refrigeration apparatus; the simplification of manufacturing and standardizing of refrigerating equipment; an improved multiple system of refrigeration; a system of refrigeration which is simple in number and construction of parts, the parts of which are of such nature and so devised that the apparatus as a whole is more rugged and less liable to get out of order than previous devices of this class while maintaining a higher efficiency of operation; to produce a direct and positive flow of refrigerant with advantages accruing thereto while controlling the flow in a manner such that refrigeration is produced in an efficient manner independently of the parts of the system collateral to evaporation; to positively return refrigerant from a float valve chamber to the compressor; to provide an arrangement wherein a standard manifold may be used with various lengths of tubing for different refrigerative capacities; and in general to improve the operation of refrigerating apparatus.

With the above and other objects in view, the invention consists in the novel features of construction, arrangement of parts and combinations of elements hereinafter described and such variations thereof as fall within the scope and spirit of invention and methods and processes involved in the operation of such apparatus.

The invention is described with reference to the accompanying drawings of which:

Fig. 1 shows more or less diagrammatically a refrigeration system embodying the principles of invention with novel parts shown more in detail;

Fig. 2 shows the system of Fig. 1 and in addition thereto means for returning lubricant from the evaporator to the compressor;

Fig. 3 shows, on an enlarged scale, the construction of a part of the apparatus of Fig. 2;

Fig. 4 shows a modification of the lubricant return means;

Fig. 5 shows another modification of the lubricant return means;

Fig. 6 shows a modification of a pressure drop member forming part of the lubricant return means;

Fig. 7 is a top view of an evaporator assembly embodying various inventive features;

Fig. 8 is a front view of the evaporator assembly of Fig. 7 shown suspended in a refrigerator cabinet;

Fig. 9 is a cross-section of a part of the apparatus of Fig. 7;

Fig. 10 is a side view of the evaporator assembly of Fig. 8;

Fig. 11 shows the lubricant return means of Fig. 2 applied to a different form of evaporator;

Fig. 12 shows a multiple system with evaporator sections connected in series;

Fig. 12a is a top view of a part of one of the sections of Fig. 12;

Fig. 13 shows a multiple system with evaporator units connected in parallel;

Fig. 14 shows a preferred form of manifold shell; and

Fig. 15 shows an adjustment for the orifice.

Referring more particularly to Fig. 1, an electric motor 2 drives compressor 3. Compressor 3 receives expanded gaseous refrigerant from conduit 24 and supplies compressed refrigerant through conduit 25 to condenser 4 which may be cooled in any desired manner, either by water or by air, though preferably by air. Condenser 4 is connected by means of conduit 7 with a valve member 23. Valve member 23 has a central passageway 27 which constitutes a portion of a continuous passageway, a part of which is within the end head 11 of float manifold 10, said passage being indicated at 26. Passageway 26 is connected to evaporator coil 15. Evaporator coil 15 is formed of one continuous pipe and its outlet end is connected to a passageway 30 formed within the other head 16 of float manifold 10, opposite to head 11. The parts hereafter described are also embodied in the apparatus shown in Fig. 3 to which reference may also be had.

Valve member 23 is screwed into a recess 28 formed in head 11. The end of passage 27, which is preferably restricted as shown in Fig. 3, constitutes a valve seat indicated at 31. Valve seat 31 cooperates with a needle valve 22. Recess 28 is formed at right angles to passage 26. Needle valve 22 is formed on the end of an extended stem 32. Stem 32 is also arranged at right an-

gles to passageway 26. Needle valve 22 is movable in response to variations of level of liquid within manifold 10, which variations of level are transmitted to the needle valve by means of a float 18 resting upon the surface of liquid within the float chamber. This movement is transmitted through lever 19, bell-crank 20 and link 21. Float 18 is attached to lever 19 which is in turn attached to bell-crank 20 pivoted at 40 on an arm 41. Bell-crank 20 is connected to link 21 and link 21 is in turn pivotally connected to stem 32 of the needle valve 22. Stem 32 passes with relatively loose fit, but at the same time closely, through a passage or bore 34 which connects the inner liquid and vapor space of float manifold 10 with passage 26. The tightness of stem 32 may be determined in accordance with the desired balance of leakage and frictional resistance.

20 By arranging the conduit from the condenser to the evaporator in part within head 11, it is possible to control needle valve 22 and thus control this conduit by a simple arrangement needing no stuffing boxes, or bellows, or other friction-producing or strained part. The amount of leakage along passage 34 outside stem 32 is of negligible quantity. By permitting this slight leakage, a simple construction is obtained. By arranging the condenser-evaporator connection 25 in part within the head no leakage is possible from out of the system as a whole.

Head 11 has an opening 12 for the reception of return conduit 24 which is connected to the intake of the compressor. In conduit 24 is inserted pressure control switch 6 which may be of known type and which starts and stops the motor on predetermined rise and fall of suction pressure. It will be understood that the system is not limited to any particular type of control 30 of the motor. Thermostatic control may be used as well as pressure control.

Reference character 9 designates a refrigerator cabinet having insulated walls bounding the space to be cooled. The evaporator assembly, 35 including manifold 10 with its heads 11 and 16 and coil 15, is entirely placed within the cabinet 9 in the space to be cooled.

The mode of operation of the system shown in Fig. 1 is as follows:

50 Gaseous refrigerant, such, for example, as methylchloride, compressed in compressor 3 passes into condenser 4 where it is liquefied and thence passes through conduit 7 and into passage 27, assuming that needle valve 22 is away from seat 31 so that the valve passage is open. Assuming needle valve 22 to be open, liquid refrigerant passes into coil 15 and a portion thereof is evaporated. Evaporation absorbs heat from the surroundings and produces refrigeration. A mixture of vaporous refrigerant and liquid refrigerant passes through passageway 30 and into the float manifold. The rise of liquid quantity within the float manifold causes a lifting of float 18 and this operates, through the mechanism above described, to close needle valve 22 against seat 31 to a greater or lesser extent, thus diminishing the flow of liquid refrigerant into the evaporator. If needle valve 22 is entirely closed, no liquid refrigerant passes from 55 the condenser through passage 27 and into the evaporator.

Assume now that needle valve 22 is closed and that the control mechanism has stopped the motor and compressor. As the space to be cooled 60 becomes warmer evaporation takes place in mani-

fold 10. This increases the pressure so that the motor is started and at the same time lowers the liquid level so that more liquid refrigerant is admitted into the evaporator. Float 18 thus operates to maintain a constant, or substantially constant, level of liquid within manifold 10. It will be noted that both manifold 10 and coil 15 partake in evaporation and therefore these two members together may be said to constitute the evaporator.

10 By means of the arrangement above described a direct positive flow is obtained through the evaporator coil. At the same time the arrangement is such that the evaporator coil is susceptible to various configurations. The advantage of 15 positiveness of float control is obtained in combination with the other features of positive flow and adaptability of structural formation.

In order to take care of lubricant for the refrigeration system above outlined, we have devised the arrangement shown in Fig. 2 which is particularly suited to cooperate with the system above defined. In Figs. 1, 2 and 3 like reference characters designate like parts. The system in general will be understood from the above description. In Fig. 2 tube 24, connected to the suction side of the compressor, is extended through head 11 into manifold 10 within the vapor space thereof. Within tube 24 is situated a restricted portion 31. This restricted portion, in the embodiment shown, is formed as the contracted portion of a Venturi tube 25. The Venturi tube has a gradually contracting passageway towards the restricted portion and a gradually expanding passageway away from the restricted portion as is characteristic with Venturi tubes. The restricted portion of the Venturi tube, otherwise known as the throat, has connected thereto a tube 26 of relatively small internal diameter or bore which extends below the surface level of liquid refrigerant within manifold 10.

The system in Figs. 2 and 3 is intended to contain a refrigerant and a lubricant of such nature that, in operation, the lubricant is dissolved in, 45 or is emulsified in, the refrigerant. Methylchloride is preferably used as the refrigerant and a mineral oil as the lubricant.

In the system shown in Fig. 1, without any means for taking care of lubricant, and with 50 lubricant contained in the system intended to go through the complete cycle, lubricant would assemble in the manifold 10. This lubricant is removed by the arrangement of Figs. 2 and 3. As the vapor passes out of Venturi tube 25 when 55 drawn by the compressor an increase in velocity is produced at throat 31 and there is a corresponding drop in pressure at this point which produces a suction acting through tube 26. This suction causes liquid to flow through tube 26 and 60 into conduit 24 and thence on to the compressor. The liquid passing through tube 26 is composed partly of refrigerant and partly of dissolved or suspended oil. The fluid passing through conduit 24 passes through evaporator coil 27 where 65 the liquid refrigerant carried over through the suction line is entirely vaporized and passes into the suction line proper as a gas together with the separated liquid oil which it formerly held in solution or suspension. Coil 27 is within the 70 space to be cooled and is a secondary evaporator. It might be called a tail coil or a drying coil.

With the apparatus shown it will be understood that the oil cannot accumulate in evaporator coil 15 as a positive flow is created through this 75

coil. The oil is made to accumulate in the float manifold 10 from which the arrangement including parts 25 and 26 draws the oil back to the compressor. It will thus be seen that our novel oil return is particularly well adapted to cooperate with the system comprising the continuous coil 15 having the ends thereof isolated and a float at a discharge end controlling a valve at the inlet end.

10 The oil entering the evaporating section with the refrigerant accumulates within the manifold 10 and the concentration of oil in the manifold increases at the beginning of operation until a point is reached where the oil drawn through tube 26 equals the entrained oil entering the evaporator section. Our arrangement therefore automatically maintains a proper flow of lubricant.

15 The invention is not limited to suspended or dissolved lubricant. Fig. 4 shows an arrangement adapted for use in a system employing sulphur dioxide as a refrigerant and having as a lubricant an oil which is lighter than sulphur dioxide and which floats on the top of the same. 20 In this case tube 26 is extended to the surface of liquid in the manifold 10 and the suction in the Venturi tube draws the oil from the surface. By using a tube 26 extending to the bottom of manifold 10 as shown in Fig. 5, the invention is applicable to a refrigerating system using ethyl-chloride or methyl-chloride with glycerine as a lubricant, glycerine being heavier than ethyl-chloride or methyl-chloride and insoluble therein. 25 In either of the two cases illustrated in Figs. 4 and 5 the second evaporator 27 is probably not necessary as there would not be sufficient liquid refrigerant entrained by the lubricant and sucked up through tube 26 to the return line to the suction side of the compressor to require a 30 second evaporator. In these cases opening 14 may be connected directly by a pipe to the suction side of the compressor. In any case, it is not desired, however, with a reciprocating type of compressor, to carry liquid refrigerant into the 35 compressor.

40 In Fig. 2 we have shown the motor 2 as controlled by a thermostatic mechanism comprising a bulb 42 connected by tubing 43 to a bellows 44, the bulb, tubing and bellows containing a vaporizable fluid and comprising a switch 45 responsive to vaporization of fluid in bulb 42, situated in the space to be cooled, for closing and opening the motor circuit. As in the previous case the evaporator is entirely placed within the space to be cooled so that evaporation may take place in manifold 10 due to heat supplied from the surrounding space to be cooled. It will be noted that the liquid within manifold 10 is in direct heat transmitting relation with the 45 circulating air of the space to be cooled.

50 Fig. 6 shows a restriction or orifice 46 which may be used for the same purpose as the Venturi tube of conduit 24. When an orifice is used the tube 26 communicates with conduit 24 a short distance in the direction of flow beyond the orifice 46. The use of an orifice causes a permanent pressure drop in the outlet conduit beyond the orifice. Such connection has also an asperating effect.

55 Figs. 7, 8, 9 and 10 show an evaporator assembly as built embodying the features of invention above described. The parts corresponding to like parts of previous figures are designated with like reference characters. The evaporator assembly comprises the manifold 10, the primary

60 evaporator coil 15 and the secondary tail coil or evaporator 27. The assembly is suspended from the roof of cabinet 9 by means of brackets 47 and 48. The coils are arranged to one side of the manifold though obviously they may be below the manifold. The coils are looped around a box 49 which contains ice trays 50. The coils are preferably arranged in good metallic connection with box 49 as by soldering. The liquid line leading from the condenser is connected to member 51. A strainer 52 is placed within member 53 which is in effect a part of head 11 of manifold 10. The arrangement of needle valve 22 and its connection with float 18 is substantially as above described. The needle valve stem 32 is 65 provided with a series of grooves 54 which serve to diminish leakage past the stem from the inside of manifold 10 to the liquid supply passage. Manifold 10 is provided with circumferentially extending axial fins 55 which serve to transmit 70 heat from the surrounding atmosphere to the liquid within the manifold. Liquid refrigerant passes through passage 27, past needle valve 22 and into the inlet end of coil 15 which is looped as indicated at 57. After passing through coil 15 refrigerant is discharged through connection 58 75 into the interior of manifold 10.

80 If desired, orifice 46 may be made adjustable from the outside of the system by using a valve-like member having a stem extending through a suitable stuffing box which can be moved to regulate the size of the orifice opening so that the suction acting through tube 26 may be regulated in order that the proper amount of liquid may be withdrawn from manifold 10. Conduit 26 is 85 connected beyond orifice 46 in the line of flow as has been explained in connection with Fig. 6 and hence, by decreasing the size of the orifice the suction in tube 26 will be increased. Thus, for example, in a multiple installation, as is shown 90 in Fig. 13, where the pressure in the different return conduits 24 adjacent the respective evaporators may be different on account of the different distances which the evaporators are from the compressor, the orifices 46 in the different 95 evaporators may be so adjusted that the suction acting through the respective tubes 26 may be the same for each tube. The outlet end 60 of tail coil 27 is connected to the suction side of the compressor.

100 We prefer to use methyl-chloride and a mineral oil in the arrangement of Figs. 7, 8, 9 and 10 as in the case of the previously described embodiments. The operation will be clear from the above description taken in connection with the 105 description of previous modifications.

110 In Fig. 11 we show the oil return of Fig. 2 applied to a loop type of evaporator as distinguished from the series coil type of evaporator of Fig. 2. In Fig. 11 manifold 10 has a series of loops 61 depending from the bottom thereof. The liquid line 7 discharges directly into manifold 10 without first going through an evaporator coil. In the arrangement of Fig. 11 the total drop in pressure between the liquid line and manifold 10 takes 115 place through needle valve 22, whereas in the previous embodiments some of the pressure drop takes place through the needle valve 22 and some through the evaporator coil. The oil return mechanism removes oil or lubricant from manifold 10 in much the same manner as in connection with the previous embodiments. It will be seen that the lubricant return mechanism is not confined to the series coil type of evaporator previously described. However, we prefer it in com- 120

bination with the same because, in the apparatus of Fig. 11, the oil return device can not so well take care of lubricant which is contained in loops 61 whereas in the arrangement of Fig. 2 there is a continuous force circulation through coil 15 which is certain to carry the oil over into manifold 10 and to the vicinity of the inlet opening of pipe 26. If desired, ice trays may be placed within loop 61 of Fig. 11 in well known manner 10 and the manifold shell may be equipped with fins.

It has been above stated that the arrangement in Figs. 1 and 2 with the coil 15 may be of various lengths and configurations. In Fig. 12 we have shown an evaporator assembly wherein a plurality of sections 62, 63 and 64 are connected in series by means of conduits 65 and 66 and connected by means of conduits 67 and 68 with manifold 10. The manifold is of substantially the same construction as in the modifications 15 above described. Sections 62 and 63 are alike and comprise a tube 70 shaped in the form of an S and to which are attached flue forming members 71 and 72. These are shown in Fig. 12a. Section 64 is similar to sections 62 and 63 but is of smaller 20 size.

The arrangement shown in Fig. 12 is intended for refrigeration in larger cabinets than the household type. This adaptation is particularly applicable to so-called commercial installations.

30 While household units can be designed for standard refrigerative effects, the requirements of commercial work necessitate different evaporator surfaces and different capacities. Our invention permits a ready adaptation to different capacities 35 for commercial work. Our system is of the flooded type or, probably more correctly, the semi-flooded type. Flooded systems usually employ a float valve which gives a more definite control than that type of valve which is generally known as expansion valve used on dry systems. 40 In previous arrangements embodying the use of a float valve complications have arisen which were overcome by means of the present invention. With the adoption of float control for the supply 45 of refrigerant to the evaporator, the float and evaporating surface have generally been combined in a unitary structure. The float being in the low pressure evaporator space, this has been deemed necessary or most expedient. The result 50 has been that where different loads are concerned, either complete evaporator units, including floats, must be used or a number of complete units, each with a separate float, must be used. The dealer or distributor of refrigerating material of this 55 type either generally has on hand a great number of different sizes of different capacity evaporators, each including evaporating surface and float, the different sizes being proportionately graded for different capacities.

60 By means of the present invention we are able to isolate the float and the float valve in a separate manifold and one size of manifold is suitable for all capacities of evaporator units regardless of differences of capacities. Furthermore the 65 manifold may be used with different sizes and shapes of evaporator tubing. The type of evaporator tubing shown in Fig. 12 is a known commercial product. It will be evident that various 70 types of tubing and extended surfaces, therefore, may be used. With this system the distributor need only have a few manifolds on hand all of the same size, and a series of standard evaporator sections such, for example, as shown at 62 and 63, with possibly a small number of odd sized 75 sections such, for example, as shown at 64.

It will be evident that sections 62, 63 and 64 may be placed alongside of each other in parallel. This would probably be the preferable arrangement in the average cabinet. They can be placed in a line, as shown in Fig. 12, which would be the preferred way for certain show-case installations having an extended evaporator in the compartment ordinarily used for ice. For this purpose the arrangement shown in Fig. 12 is particularly suitable as it gives a series of vertical 10 flues formed by the member 71, 72.

The operation of the apparatus of Fig. 12 is the same as that in previous modifications. This modification includes the oil return device and the tail coil 27 for evaporating any refrigerant 15 entrained into pipe 26 or otherwise carried from the manifold in direction toward the compressor.

Referring to Fig. 13 the apparatus described above is shown in an arrangement suitable for use with a plurality of evaporators. As shown, 20 one condenser is employed but it is to be understood that a separate condenser may be employed for each evaporator, or two evaporators supplied from one condenser and one evaporator from another condenser, or any such combinations of condensers and evaporators may be employed without departing from the spirit of the invention. Also, any number of evaporators may be used, three merely being a convenient number for illustration.

30 Compressed gaseous refrigerant leaves the compressor through conduit 25, is liquefied by condenser 4 and passes into pipe 5. During its passage through pipe 5 the liquid refrigerant divides and passes through the various pipes denoted by reference character 7. From conduits 7 the refrigerant passes through respective float actuated expansion valves, evaporators 15 and manifolds 10 in the same manner as previously described with reference to a single manifold 40 system. The amount of liquid refrigerant entering each evaporator coil through the expansion valve used in connection with that coil is dependent on the liquid level in the float chamber of that float actuated expansion valve and is independent of the liquid level in any of the float chambers or any other conditions existing in the system.

The vaporous refrigerant after leaving manifold 10 passes through the respective pipes 24 50 to a common return pipe 14 which is connected to the suction side of the compressor. Interposed in this pipe 14 may be the pressure control switch 6 used to start and stop the motor at predetermined valuations of pressure in the suction line. 55

Fig. 14 shows a preferred form of shell for manifold 10. The shell is made of a single brass plate and is drawn to the form shown making a single unitary drawn member composing the major portion of the manifold. The flange portion 76 is connected to a suitable head containing the needle valve and supporting the float. The opening 77 serves for the reception of a member containing the conduits connected to the manifold at that end.

65 Fig. 15 shows an outside adjustment for the orifice as above referred to. 10 designates the manifold shell and 26 designates the tube connecting the liquid space of the manifold with the reduced pressure space of the return line 70 from the manifold toward the compressor. The orifice member 46 is situated in a sleeve 79 which is fitted into the opening 77 of Fig. 14. A spindle 78 carries a valve 80 which is adapted to be moved into and out of the orifice to change its 75

size. Stem 78 is connected to a threaded portion 81 which is adapted to be screwed into member 79. Packing 82 is inserted between a ring 83 and a threaded retaining member 84. A cap 85 fits over the end of member 78. 86 designates a threaded opening for a connection to the suction line leading to the compressor. This type of adjustment or similar adjustments may be applied to the orifices of any of the previously described 10 embodiments of the invention.

While we have shown and described various 15 embodiments of our invention, it will be understood that we are not limited to the apparatus shown or described but that a great many variations are permissible within the spirit and scope of the invention.

Having thus described our invention, what we claim is:

1. A refrigerator comprising a cabinet having 20 insulated bounding walls defining a space to be cooled, an evaporator within said space comprising a manifold having an outer shell and providing a chamber for containing a body of liquid refrigerant, a passageway for liquid refrigerant extending within said shell and sepa-

rated from said chamber, a valve in said passageway, means responsive to variations of surface level of liquid in said chamber for moving said valve to vary flow of liquid refrigerant through said passageway, evaporator tubing connected to said passageway and arranged to conduct fluid from said passageway to said chamber, said tubing comprising a series of standard sections each made up of tubing with members forming extended surfaces attached thereto, said members forming flues for passage of air past the tubing, said tubing passing through the space to be cooled and said shell acting to transmit heat from the space to be cooled directly to the body of liquid in said chamber.

2. A refrigerator comprising a cabinet having insulated bounding walls defining a space to be cooled, an evaporator within said space comprising a manifold, tubing connected to said manifold and a tail coil connected to receive 20 vapor and liquid from said manifold, said tail coil being situated in the space to be cooled to evaporate refrigerant therein.

FRANK DESNOYERS PELTIER. 25
